[57] ABSTRACT

An electronic watch comprising a motor for converting electrical energy into mechanical rotational movement, an actuating means operable from the outside of the casing of the watch, and an arbor means for the hand of the watch. A gear train couples the motor to the arbor means and a cam means is operatively connected to the actuation means and the watch hands. The cam means are controlled by the operation of the actuation means for setting at least one of the hands of the watch to a reference position whereby the watch may be set by merely operating the actuation means.

FIG. 6

TIME-SETTER FOR AN ELECTRONIC TIMEPIECE

This invention relates to improvements to electronic watches, and more specifically, it relates to improved correction mechanisms adapted for correction of time indicating-hands for keeping desired correct time display.

In the case of conventional mechanical or electronic watches, clutch means, preferably of the frictional type, must be provided in the gear train arranged between time indicating hand arbor and the escapement, for release of excess torque at this clutch means when it develops as the time-setting operation of a heart cam member or the like. However, the provision of such clutch means inserted in the gear train will make the latter into a highly complicated design and arrangement, an increased thickness of the timepiece movement and a substantial difficulty in the arrangement of such gear train.

The main object of the present invention is to provide an improved time-indicator correction mechanism, devoid of such additional mechanical clutch means in the gear train, for obviating the above mentioned conventional drawbacks.

For attaining such object as above, an electronic watch is provided which includes means for conversion of electrical energy into a corresponding mechanical rotational movement, and a time-display hand correction cam means controllable by manipulation of an operating member, preferably a push button manipulatable from the outside of the watch movement. A gear train extends between said motion conversion means and an arbor for said time-display hand, thus excess torque developed by the correction operation of said correcting cam is released through said motion conversion means per se.

These and further objects, features and advantages of the invention will become more apparent as the description by reference to the accompanying drawings.

In the drawings:

FIG. 1 is a schematic plan view of the first embodiment of the invention in its regular operating state.

FIG. 2 is a similar view to FIG. 1, wherein a time-setting button of the timepiece has been pushed in for adjusting the time-indicating hands to a desired hour time.

FIG. 3 is a part of the timepiece movement shown in FIGS. 1 - 2, wherein the operation is such that a certain selected minute time has been set.

FIG. 4 is a sectional view taken along a broken section line IV - IV' shown in FIG. 1.

FIG. 5 is an enlarged and somewhat modified part of FIG. 4, constituting the second embodiment of the invention.

FIG. 6 is a similar view to FIG. 1, showing the third embodiment of the invention.

Referring now to the accompanying drawings, illustrative of three preferred embodiments of the invention, the invention will be described in detail hereinbelow and by way of example only.

In FIGS. 1 - 4, numeral 1 represents only partially a base plate, such as pillar plate, on which a motion-transmitting lever 2 is pivotably mounted at 3. This lever 2 comprises first or uppermost element 2A, a second or middle element 2B and a third or lowermost element 2C fixed rigidly together by means of pins 2a and

5 2b. The first lever element 2A comprises a first elongated resilient arm 2c. In the similar way, the second lever element 2B comprises a second elongated resilient arm 2d. The third lever element 2C is provided with a third angular-shaped, rather rigid arm 2e.

An urging spring 4 has a root portion 4a which is fixedly attached to the base plate 1 by means of pins 10 and 33, an intermediate bent portion 4b which is kept normally in pressure-contact with a shoulder 13 formed 10 on the plate 1, and a tip end portion 4c which is kept always in pressure contact with the arm 2 for urging resiliently the latter to turn clockwise in FIG. 1 around its pivot pin 3.

Numeral 5 represents a first cam which is fixedly attached 15 to a conventional seconds hand arbor 6 for return operation of the seconds hand, not shown, as will be more fully described hereinafter. There is provided a second cam 7 which is fixedly attached to a conventional minute hand arbor 8 for return operation of the 20 minute hand, not shown, as will be more fully described hereinafter. The first cam 5 has preferably a heart cam configuration as shown, while the second cam 7 has a generally disc configuration having a relatively large peripheral notch 7a as a preferred shape shown in 25 FIGS. 1 - 3.

A first cam control lever 9, having generally a L-shape when seen in FIGS. 1 and 2, and comprising an elongated, slightly resilient arm portion 9c and a root portion 9d made integral therewith, and its root portion 30 9d is pivotably mounted on the pin 10, while its arm portion 9c is formed at its tip end with an active surface 9a and a curved recess 9b as shown. When the lever 9 is brought into its operating position, the active surface 9a is kept in contact with the cam 5, as shown in FIG. 2. Thus, the lever 9 is shown in its regular and non-operating position in FIG. 1. For this purpose, the first 35 resilient arm 2c is kept in pressure contact with a projection 9e of the lever 9 which defines partly the recess 9b, thereby the last mentioned lever 9 being normally 40 kept in its non-operating position shown in FIG. 1. The extreme position is defined by a stationary stop pin 14 which is studded on the base plate 1.

A second cam control lever 11 is pivotably mounted 45 on the base plate 1 at 12. This lever 11 is formed with an operating end 11a, a curved recess 11b and a projection 11c, the latter being normally kept in pressure contact with the tip end of the second lever arm 2d of said lever 2 for keeping the cam control lever 11 in its 50 non-operating position shown in FIG. 1. When the lever 11 is brought into its operating position, the operating end 11a is kept in physical contact with the second control cam 7 as shown either in FIG. 2 or 3, as the case may be. In the non-operating position of the second cam control lever 11, the tip end of the second resilient arm 2d of lever 2 is kept in contact with the projection 11c. For defining the extreme non-operating position of the lever 11, there is provided a stationary shoulder 15 on the base plate 1 for cooperating the lever projection 11c.

A conventional minute hand pinion 8a is made rigid 60 with the arbor 8. A conventional second wheel 16 is loosely mounted on the arbor 8. A seat ring 17 is made rigid with the arbor 8 on which the inner periphery of a perforated disc spring 18 abuts, while the latter is kept in pressure engagement by its outer peripheral zone with the second wheel 16, thus this wheel being resiliently urged axially upwards against second cam 7.

In this way, a kind of friction clutch is provided by the combination of seat 17 and disc spring 18 being the second wheel 16 and the minute hand arbor 8.

Conventional seconds hand pinion 6a is made integral with the arbor 6 and conventional fourth wheel 6b is arranged rigidly with the same arbor 6. Third wheel 19 comprises a third gear 19a and a third pinion 19b made rigid with each other. Third pinion 19b meshes with second wheel 16. Fifth wheel 20 meshes with fourth wheel 6b. Sixth wheel 21 comprises a gear 21a and a pinion 21b made rigid with each other, the sixth pinion 21b meshing with said fifth wheel 20. Indexing wheel 22 comprises a gear 22a and a pinion 22b made integral with each other; the indexing pinion 22b meshing with said sixth gear 21a, while the indexing gear 22a is adapted for periodical cooperation with a conventional impulse pin 24b mounted on a cam 24a comprised in a drive balance wheel assembly 24. Indexing gear 22a is stepwise positioned magnetically by a stationary positioning magnet 23 mounted on the base plate 1, when the timepiece movement goes. For attaining the driving nature, the balance wheel assembly is provided with two pairs of permanent magnets, of which only a pair is shown schematically at 33 in FIG. 4, arranged to cooperate with stationary coil means 34 shown only schematically and partially therein.

Numerical 25 represents a conventional cannon wheel which is rotatably mounted on the minute hand arbor 8 and provided with an hour hand, not shown. Numerical 26 represents a conventional minute wheel having a gear 26a and a pinion 26b made rigid therewith. The minute pinion 26b meshes as conventionally with the cannon wheel 25, while the gear 26a meshes with the minute hand pinion 8a.

Numerical 27 represents a balance stop lever which has a pivot pin 32 studded on the base plate 1. This lever 27 is formed integrally with rigid projections 27a, 27b and 27d and with an elongated and resilient arm 27c which is kept in pressure contact with a stop pin 28 studded on the plate 1. The second projection 27b is kept in pressure engagement with the rigid arm 2e of the motion-transmitting lever 2 when the balance stop lever 27 is in its off-service position shown in FIG. 1. In this case, the lever 27 is subjected resiliently to a clockwise turning effort accumulated therein around its pivot 32, when freed from contact with said rigid arm 2e, as clearly seen from comparison of FIG. 1 with FIG. 2. With clockwise pivotal movement of the stop lever 27, the first projection 27a thereof is brought into cooperative engagement with stop cam 24a which is rigidly and concentrically attached on the balance wheel arbor shown at 24c. The clockwise turning movement of the freed stop lever 27 is limited by contact of its third projection 27d with a land 29 formed integrally on the plate 1.

Numerical 30 represents schematically and partially a self-contained battery which feeds currents through a conventional transistored drive circuit, not shown, to the coil means 34, although the wiring connections have been omitted from the drawing only for simplicity.

Numerical 3' represents an outside operating member, preferably in the form of push button or reciprocatingly operable stem, such as conventional time-setting stem, arranged for cooperation with one end of the motion-transmitting lever 2, although its bearing means and re-

turn spring have been omitted from the drawing only for simplicity.

The operation of the first embodiment so far shown and described is as follows:

It is now assumed that the accurate present time is just 9 hour 0'-0" and the timepiece fitted with the foregoing embodiment displays 9 hour 03'-20".

When the timepiece user wishing to set his timepiece representation to the correct time, he depresses push button 3' from its outer non-operating position shown in FIG. 1 to its inner operating position shown in FIG. 2.

Motion is thus transmitted from push button 3' to lever 2 so that the latter is turned counter clockwise about its pivot pin 3 in FIG. 1 to occupy its operating position shown in FIG. 2. By this pivotal movement of the lever 2, motion is further transmitted through its respective arms 2c and 2d to first and second cam control levers 9 and 11, respectively, so as to turn clockwise these levers from their position shown in FIG. 1 to that appearing in FIG. 2. At the same time, the resiliently urged balance stop lever 27 is released from contact by its second projection 27b with the rigid arm 2e of motion-transmitting lever 2 and turns clockwise a certain predetermined angle around its pivot pin 32, until its first projection 27a will have been brought into its cooperating position with either projection 24d or 24e of stop cam 24a on the oscillating balance wheel assembly, 24 as was only briefly referred to hereinbefore, thereby the latter being positively prevented its oscillating movement and kept stationary. At this stage, conventional hair spring 24f fitted to the balance wheel assembly is held under tension for ready for quick restarting thereof, and the impulse pin 24b is held at its non-operating position relative to its regularly cooperating indexing gear 22a which is thus freed without receiving any driving torque from the balance wheel assembly. In practice, however, the indexing gear is kept stationary under the influence of attracting magnetism emanating from the positioning magnet 23.

With clockwise pivotal movement of first cam control lever 9, its active end surface 9a is brought into contact with first cam 5, thereby the latter being forcibly turned to its zero position corresponding to that of the seconds hand. This position is shown in FIG. 2. Since such a zero return heart cam mechanism is known per se and thus no detailed description thereof would be necessary for better understanding of the invention.

With clockwise pivotal movement of second cam control lever 11, its operating end 11a is brought into engagement with the notch 7a of second cam 7, thereby the latter being forcibly returned to its zero position corresponding to that of the minute hand. At the same time, the hour hand is returned to its nine o'clock position in this case. Thus, the corresponding time indication will be 9.00.

In this case, the ratio in returning angle between the second cam 7 for minute hand and the first cam 5 for seconds hand is 3 : 20 and thus different from the regular rate 1 : 60. Therefore, there must be a certain amount of slippage between the minute hand arbor 8 and the seconds hand arbor 6. For this purpose, the aforementioned clutch comprising the combination of seat 17 and disc spring 18 serves well.

Although, in this case, torque is reversely transmitted from seconds hand arbor 6 through fourth wheel

6b, fifth wheel 20, sixth pinion 21b, sixth gear 21a and indexing pinion 22b to indexing gear 22a which will thus be rotated to a certain degree in the reverse direction against the positioning action of the magnet 23. Thanks to the aforementioned operative interruption between impulse pin 24b and indexing gear 22a, there is no adverse effect caused thereby.

In the present specific embodiment, the notch 7a is so dimensioned as to cover an adjustable range of ± 4 minutes, which range may naturally be modified as occasion desires.

Next, it is assumed that the correct time is 9 hour 20' - 0" and the time display of the watch is 9 hour 20' - 35".

Under this condition, when the watch user depresses the push button 31 as before, both cam control levers 9 and 11 are turned clockwise in the similar way. In this case, however, the operating end 11a of second cam control lever 11 is brought into contact with the lobe surface of second cam 7 exclusive of the notch 7a, as shown in FIG. 3, thereby no positive turning effort being provided thereupon. However, the second arm 2d of the motion-transmitting lever 2 is brought into a certain resiliently flexed position. Practically at the same time, the active surface 9a of first cam control lever 9 is brought into cooperation contact with the first cam 5, as shown in FIG. 3, thereby the cam together with seconds hand arbor 6 being turned forcibly and counter clockwise in FIG. 3 an angular range corresponding to 25" or (60" - 35"), so as to set the seconds hand to its zero position. FIG. 3 shows the position of first cam 5 corresponding to this newly zero-set one. With such setting rotation of the first cam 5, the second cam 7 will be slightly rotated in the same direction at the ratio of 1 : 60. Since the lobe surface of second cam 7 has been finished highly smoothly, the operating end 11a of second cam control lever 11 can slide without hindrance. Thus, the minute hand will be moved to the position of 20'. In this way, the correct time-setting operation has been completed in this case. In this case, the clutch 17-18 will naturally not slip. The operation of the indexing wheel 22 is as before. It will be seen from the foregoing description and by reference to the heart cam configuration at 5 that ± 30 seconds error in the time display representation can be accomplished either in the return or advancing mode, as occasion may desire.

Although in the foregoing description, it has been disclosed for simplicity that the operations of the first and second cam control levers 9 and 11 and of the balance stop lever 27 may be brought about substantially at the same time. However, in practice, it should be mentioned that the operation of the balance stop lever 27 must be carried out somewhat earlier than those of the first both levers 9 and 11. If not, and thus when the balance wheel assembly 24 is kept in its regular oscillating position and the indexing wheel 22 should be rotated from the side of the time correction mechanism, the teeth of the indexing gear 22a could be brought into collision with impulse pin 24b on stop cam 24a of the balance wheel assembly 24, thereby the wheel teeth and impulse pin being subjected to heavy damage.

It should be further noted that if the second cam control lever 11 should be brought into operation earlier than the first cam control lever 9, an unintentional quick rotation of the seconds hand will be invited by the rotation of the second cam 7, which, when brought

about, would give the watch user a highly unpleasant feeling. In order to prevent such operational defect, the related parts are so dimensioned and arranged that only after the first cam control lever 9 has been brought into the locus sphere of the first cam 5, the second cam 7 will initiate its rotational movement for time display correction.

Next, the second embodiment shown only in its essential parts in FIG. 5 will be described. It should be noted at this stage that other constituent parts than those shown may be same as those of shown in the foregoing first embodiment. Further note that same or similar parts shown as those of the first embodiment have been denoted with respective same reference numerals, each being added with 100 for quicker and clearer comparison with the first embodiment.

Numerical 105 represents a first cam attached fixedly to seconds hand arbor 106. As seen, this cam 105 has a heart shape as before.

Second cam 107 is attached fixedly to a minute hand arbor, not shown, or to a further arbor, again not shown, operatively connected therewith. Although not shown, there is provided a mechanical clutch means, preferably a friction clutch of known design, between the seconds hand arbor 106 and the cam 107. Numerals 109 and 111 represent first and second cam control levers, as before, which are shown, however, only partially and schematically. The cam 107 is formed with a number of successive peripheral saw tooth recesses 107b each of the latter having a peripheral coverage corresponding to a minute, together with a large notch 107a having similar configuration and function as those of the foregoing notch 7a.

When the minute hand is positioned within an offset range of ± 4 minutes relative to a certain correct time, operation of the first cam control lever 109 by manipulation of a push button, not shown, similar to the foregoing button 31 will influence upon the first cam 105 for correct zero-setting of the seconds hand as described hereinbefore. By operation of the second cam control lever 111, it is brought into engagement with the notch 107a on the cam 107 for correct setting of the minute- and hour hands as before.

The force received by the first cam 105 for the correction of seconds hand from the lever 109 can be released by idle rotation of the indexing wheel as at 22 in the foregoing embodiment. The rotational difference between the cams 107 and 105 caused by the both kinds time correction operations can be well compensated by the clutch means provided between the arbor 106 and cam 107 in the similar manner as explained in the foregoing first embodiment.

Even when the minute hand is situated outside of the aforementioned ± 4 minutes offset range actuation of the push button corresponding to 31 will bring the seconds hand arbor to its correct zero position under the influence of the first cam control lever 109 as before. The second cam control lever 111 will enter one of the serrated recesses 107b on the cam 107, thereby the minute- and hour hands being corrected to their correct position. The hour hand is corrected, since it moves in conjunction with the minute hand. Thus, when the minute hand is corrected, it moves the hour hand a very small amount. More specifically, the aforementioned functional cooperation of the second cam 107 with first cam 105 will bring all the hour-, minute- and seconds hands to their correctly interrelated relative position

corresponding as to show the desired correct time display positions.

Although in the foregoing embodiments, the motion receiving notch 7a or 107a has been shown and described as singular, the number of the notches can be increased to a certain plural. In this way, when the minute hand is situated, as an example, within the range of $30 \pm$ several minutes or $45 \pm$ several minutes, relative to the correct time such as 35' or 45', respectively, it can be set thereto, as will be easily understood from the foregoing description.

Referring finally to FIG. 6, the third embodiment will be described in detail. In this embodiment, the invention has been applied to a quartz wrist watch. In this embodiment, same or similar parts as those used in the first embodiment will be shown by same reference numerals, each being added with 200 for easy comparison and better understanding.

In the present embodiment, the motion converter adapted for conversion of electrical energy into a corresponding mechanical and rotational movement has been embodied into a miniaturized stepping motor, as will be more fully hereinbelow, hereinbelow.

Numeral 206 represents a second hand arbor to which a conventional fourth gear 206b and the first or seconds hand correction cam 205 which is shaped as before into a heart cam. The fourth gear 206b is shown only schematically and as partially broken away. The miniaturized stepping motor is shown at 250, having a stator 251 and a rotor 252 magnetically coupled therewith. The rotor is provided with its shaft 252a rigid therewith and rotatably mounted in suitable bearing means, not shown, which is mounted in turn in base plate 201, preferably conventional pillar plate only partially shown, and a bridge member, supported rigidly thereon although not shown. The rotor 252 further comprises a 6-pole permanent magnet 252b having alternatively and radially arranged N- and S-poles, a 6-teeth ratchet wheel 252c for reverse rotation preventing purpose and a pinion 252d. These magnet 252b, ratchet wheel 252c and pinion 252d are made rigid with the rotor shaft 252a, said pinion meshing with said fourth gear 206b, as schematically represented.

The stator 251 comprises a pair of oppositely arranged stator halves 251a and 251b rigidly mounted on base plate 201 although their mounting means have been omitted only for simplicity. The stator 251 is fitted rigidly with an energizing coil 251c having its terminals shown at 251d and 251e which are electrically connected with a conventional transistored electronic drive circuit of conventional design and including a quartz or crystal oscillator, although not shown, for being fed with a pulsative a.c. current as schematically shown at the lower left corner in FIG. 6.

An elongated and resilient spring strip 253 is fixedly mounted with its root portion on the base plate 201 by means of a collet 253a which is kept in pressure fit on a stud pin 201b studded on the plate 201, while the tip end of the strip 253 is kept in engagement with one of the teeth of said ratchet 252c, thus the latter being allowed only one way stepping rotation as shown by a small arrow in FIG. 6.

Although not shown, motion-transmitting lever 202, only partially shown, is adapted for performing a pivotal movement substantially in the direction shown by an arrow alpha when mechanically urged by intentional depression of a push button, similar to that shown at 31

in FIGS. 1 and 2. The lever 202 is formed with a slot 202a and a projection 202b. The pivot pin, as at 2b in FIGS. 1 and 2, has been omitted from the drawing only for simplicity. An urging spring as at 4 in the foregoing has been omitted only for the same purpose. Normally, the lever 202 is kept in its off-service position shown in FIG. 6.

Seconds hand setting lever 209 is pivotably mounted on the base plate 201 by means of a pivot pin 210 studded thereon, and fitted with a motion-receiving pin 209b which is studded on the setting lever 209 and kept in loose engagement with said slot 202a. Numeral 209a represents the actuating or operating end of the lever 209.

A further lever 227 is pivotably mounted through its pivot pin 232 studded on the base plate 201. A spring bend 227c is inserted between the lever 227 and a land 201a on the plate 201, thus the lever being urged to rotate clockwise in FIG. 6 around its pivot pin 232 and kept stationary by contact of its stop pin 227b with the projection 202b of the motion-transmitting lever 202. In close proximity to said spring strip 253, an actuating pin 227a is provided on the lever 227. When this lever 202 is rotated clockwise in FIG. 6 about its pivot pin, the pin 227a is brought into collision with the spring strip 253 which is thus disengagement from meshing with the ratchet wheel 252c.

The operation of the last embodiment so far shown and described is as follows:

When a series of a.c. driving pulses as shown at the lower left corner of FIG. 6 are fed from the electronic driving circuit, having a crystal oscillator as a time base of the watch, through terminals 251d and 251e to the energizing coil 251c, thus the stator halves 251a and 251b being magnetized oppositely to each other and in the alternative way. Therefore, the rotor 252 will rotate one step (one-sixth of a complete rotation) clockwise in FIG. 6 for every reception of one pulse. The spring strip 253 serves for prevention of occasionally and unintentionally caused reverse rotation of the rotor. Further, it acts as a vibration damper for the rotor.

The thus caused stepwise rotation of the rotor is transmitted through pinion 252d and gear 206b to seconds hand arbor 206, and so on.

When the watch user depresses an actuating member such as the push button as at 31 adopted in the foregoing embodiments, motion-transmitting lever 202 is pivotally moved as shown by the arrow alpha. At the first stage, the projection 202b collides against the pin 227b, thereby the lever 227 being pivoted counter clockwise in FIG. 6 for disengaging the spring strip 253 from engagement with ratchet wheel 252c.

Since, at this stage, the electric drive pulses are fed to the energizing coil as regularly, the rotor can continue its steppingly rotational movement without hindrance. At this stage, the rotor is kept in magnetic coupling with its stator, although the coupled state is variable. It should be noted that the rotor can be driven in either rotational direction, as the case may be, when an appreciable driving torque overcoming said magnetic coupling is applied to the rotor.

With further pivotal operation of the lever 202, the seconds hand setting lever 209 is caused, thanks to the pin-and-groove connection 209b; 202a, to make a clockwise pivotal movement around its pivot pin 210 and its operating end 209a is brought into its cooperating contact with the cam 205. In this way, the seconds

hand, not shown, is corrected to its correct position in the similar way as before. Rotation is therefore transmitted from the seconds hand arbor 206 to the minute hand arbor, not shown. The minute hand is also correspondingly rotated and thereby adjusted.

Rotation of the arbor 206 accompanies the gear 206b in unison and thus, the arbor 252a together with the rotor are rotated by gear-meshing between gear 206b and pinion 252d, and upon overcoming the inherent magnetic coupling within the interior of the stopping motor 250, the rotor is corrected in its position relative to the stator. Thus, it will be seen that there is no needs of the provision of clutch means between the seconds hand arbor 206 and the motion-conversion mechanism.

In a modification, not shown, the current motion-converter may exclusive a tuning fork, a piezoelectrical drive means or so for oscillative drive thereof, a feed spring pawl (pallet) mounted on said tuning fork, a number of feeding teeth on a ratchet wheel adapted for engagement with said feed pawl, and a stop pawl (pallet) adapted for preventing any reverse motion of the ratchet. Also, in this case, the arrangement is so that these stop- and feed pawls or pallets may be disengaged so as to bring the ratchet wheel into its freely rotatable state for attaining the same purpose.

The embodiments of the invention in which an exclusive property of privilege is claimed are as follows:

1. In an electronic watch comprising:

- a. conversion means for converting electrical energy into mechanical rotational movement;
- b. actuation means operable from the outside of the casing of said watch;
- c. a first arbor for the seconds hand of said watch;
- d. a second arbor for the minute hand of said watch;
- e. gear train means coupling said conversion means to said first arbor;
- f. clutch means for allowing relative slippage between said two arbors;
- g. first cam means, of a heart configuration, fixedly attached to said first arbor;
- h. second cam means, of a notched disc configura-

- tion, fixedly attached to said second arbor;
- i. motion-transmitting lever means for receiving motion from said actuation means;
- j. a first cam control lever means for receiving motion from said motion-transmitting lever means and for cooperating with said first cam means so as to correct said seconds hand to its zero-position and to correct said minute hand to its correct minute indicating position;
- k. second cam control lever means for receiving motion from said motion-transmitting lever means and for engaging the notch of said second cam means for correcting said minute hand to its zero-position;
- l. lever means responsive to said motion from said motion-transmitting means, thereby stopping said conversion means in its operation and for disconnecting said train means; and,
- m. a resilient means, provided in the path of motion transmission extending from said actuating means to said second cam control lever means, for correcting only said first cam in its position when said second cam control lever means engages said second cam at any position other than said notch.
- 2. An electronic watch such as claimed in claim 1, wherein said motion-transmitting lever means comprises a first and second resilient arm held in pressure engagement with said first and said second cam control lever, respectively.
- 3. An electronic watch such as set forth in claim 2 wherein said motion converting means comprises a drive balance wheel and an index wheel held in cooperation therewith, wherein said lever means for stopping said motion conversion means and for decoupling said motion conversion means from the gear train, said first cam control lever means and said second cam control lever means are sequentially operated by actuating said actuation means.
- 4. An electronic watch such as set forth in claim 3, further comprising a series of serrations formed on the periphery of said second cam for correcting said second arbor to the correct minute position.
